UNITED STATES PATENT OFFICE

WILLIAM W. KENT, OF BRONXVILLE, NEW YORK, ASSIGNOR TO ELLICOTT SQUARE COMPANY, OF BUFFALO, NEW YORK, A CORPORATION OF NEW YORK

DESIGN FOR A MOSAIC FLOOR OR SIMILAR ARTICLE

Application filed September 8, 1930. Serial No. 36,897. Term of patent 14 years.

To all whom it may concern:

Be it known that I, WILLIAM W. KENT, a citizen of the United States, residing at Bronxville, in the county of Westchester and State of New York, have invented a new, original, and ornamental Design for Mosaic Floor or Similar Article, of which the following is a specification, reference being had to the accompanying drawing, forming a part thereof.

The single figure of the drawing is a plan of the mosaic floor embodying my design, the

repeated detail of the design being shown complete in a portion only of the figure, and one corner being broken away for convenience of illustration. The floor shown in the drawing is a definite and complete article of manufacture.

I claim:

The ornamental design for a mosaic floor or similar article substantially as shown and described.

WILLIAM W. KENT.
